UNITED STATES PATENT OFFICE.

HOWARD A. THOMPSON, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed September 2, 1924. Serial No. 735,236.

My invention relates to railway traffic controlling apparatus, and particularly to apparatus of the type comprising governing mechanism on the train controlled by means 5 located in the trackway.

Apparatus embodying my invention is intended more specifically for stretches of railway track used by trains of different classes having different maximum braking distances. For example, the track may be used 10 by passenger trains having relatively short maximum braking distances, and also by freight trains having relatively long maximum braking distances. In order to bring 15 these two classes of trains from a given speed to a stop at a fixed point, the brakes on the passenger train should be applied at one distance in the rear of the fixed point and the brakes on the freight train should be applied 20 at a greater distance in the rear of the fixed point. One feature of my invention is the provision of means for selecting the point of 25 brake application in accordance with the class of the train which is using the track.

I will describe one form of apparatus embodying my invention, and will then point out the novel features thereof in claims.

In the accompanying drawings, Fig. 1 is a diagrammatic view showing one form of trackway apparatus embodying my invention. Fig. 2 is a view showing diagrammatically a passenger train, and Fig. 3 is a view showing diagrammatically a freight train, both of which trains are adapted to use 30 the railway track shown in Fig. 1.

Referring first to Fig. 1, the reference characters 1 and 1^a designate the track rails of a railway along which traffic normally moves in the direction indicated by the arrow. The stretch of track shown in the drawing is the stretch between two adjacent stations A' and A^a, and this stretch is a complete unit of a system which may be formed 40 by placing a plurality of such units end to end. When this is done, the right-hand half of station A' would become the right-hand half of station A^a, and so on.

The stretch of track shown in the drawing is divided by insulated rail joints into a plurality of sections B—C, C—D, D—E and E—B. The section E—B, containing the station A, is here shown as being a gauntlet track, comprising an inner pair of rails 2, and an outer pair of rails 3. The reason for

this is that the apparatus is designed for a 55 railway on which the freight trains are wider than the passenger trains. If only one track were provided at the stations, and if this track were far enough away from the station platforms to permit the freight trains to 60 pass, then the passenger trains would be too far from the platform for safety. The gauntlet tracks are accordingly so arranged that the passenger trains take the inner track rails 2, so that their platforms are the proper 65 distance from the station platforms, whereas the freight trains take the outer track rails 3, so that they clear the station platforms by a safe margin. Located at the right-hand end of each gauntlet track is a switch N', and 70 located at the left-hand end of each gauntlet track is a switch N^a. These switches are operated by suitable means, not shown in the drawing for the reason that such means forms no part of my present invention. It 75 is, of course, understood that in practice the two switches for each gauntlet track will be operated simultaneously. When a passenger train approaches a station the two switches will be in normal positions, so that this train 80 will take the inner track rails 2, whereas, when a freight train approaches a station the two switches will be in reverse positions, so that this train will take the outer track rails 3.

Each track section is provided with a track circuit comprising a source of current located at the exit end of the section and a track relay located at the entrance end of the section. As here shown, the source of track 85 circuit current is a track transformer designated by the reference character G with an exponent corresponding to the location, the secondary of which transformer is connected directly across the track rails through a current-limiting impedance 5. The track relay for each section is designated by the reference character H with an exponent corresponding to the location. The two gauntlet 90 tracks 2 and 3 at each station are connected 95 in multiple by bonds 54, so that a train on either track will open the track relay H^a.

The primary of each track transformer G is connected with the secondary of an adjacent line transformer designated by the reference 100 character F with an exponent corresponding to the location, and the primary of each line transformer F is connected with a transmis-

sion line L which is constantly supplied with alternating current by a generator M.

Located at the point B is a signal S^B , which governs traffic through the stretch B—C. This signal in the form here shown is a three-position semaphore signal arranged to indicate "stop", "caution" and "proceed". This signal is controlled by the adjacent track relay H^B and also by relays J and P^B . The control of the two latter relays, is as follows:

Relay J is provided with a circuit which passes from the secondary of transformer F^C , through wires 17 and 18, contact 19 of track relay H^C , wires 20 and 21, winding 15 of relay J, wire 22, wire 6, common wire 0, and wires 23 and 25 to the secondary of transformer F^C . It follows that relay J is a repeater for track relay H^C and will therefore be energized at all times except 20 when section C—D is occupied.

Relay P^B is provided with a circuit which passes from the secondary of transformer F^D , through wires 26 and 27, front point of contact 28 of track relay H^D , wires 29 and 30, front point of contact 31 of track relay H^C , wires 32 and 33, contact 34 of relay H^B , wires 35 and 36, winding of relay P^B , wires 37 and 6, common wire 0, and wires 38 and 40 to the secondary of transformer F^D . It follows that so far as this circuit is concerned, relay P^B will be de-energized whenever any one of the track relays H^B , H^C or H^D is de-energized, that is, whenever there is a train at any point between B and E. Relay P^B is provided with a stick circuit which passes from transformer F^C through wires 17 and 18, contact 19 of relay H^C , wires 20 and 20^a, back point of contact 65 of relay H^B , wire 64, contact 63, wires 62 and 36, winding of relay P^B , and wires 37, 6, 0, 23 and 25 to transformer F^C . If relay P^B is closed when a train enters section B—C it will remain closed until the train leaves this section because of this stick circuit. Relay P^B may be made sufficiently slow-releasing to bridge the interval between the opening of its pickup circuit at contact 34 and the closing of its stick circuit at contact 65, or the contacts of relay H^B may be so adjusted that the back point of contact 65 closes before contact 34 opens. Relay P^B is provided with other circuits which will be explained hereinafter.

Signal S^B is provided with a caution indication circuit which passes from the secondary of transformer F^B , through wires 6 and 7, contact 8 of relay J, wire 9, contact 10 of relay H^B , wires 11 and 12, the operating mechanism of signal S^B , and wire 13 to the secondary of transformer F^B . This signal is also provided with a proceed indication circuit which passes from the secondary of transformer F^B , wires 6 and 7, contact 8 of relay J, wire 9, contact 10 of relay H^B , wires 11 and 14, contact 15 of

relay P^B , wire 16, operating mechanism of signal S^B , and wire 13 to secondary of transformer F^B . It follows that when either track section B—C or C—D is occupied by a train, signal S^B will indicate stop because either relay H^B or relay J will then be de-energized and so the caution indication circuit for signal S^B will be opened at either contact 10 or 8. It also follows that in so far as the circuits thus far traced for relay P^B are concerned, signal S^B will indicate proceed only when sections B—C, C—D and D—E are unoccupied. That is to say, if there is a train in section D—E but no train in the other two sections, relays H^B and J will be energized, so that the caution indication circuit for signal S^B will be closed, but relay P^B will be de-energized so that the proceed indication circuit for this signal will be open at contact 15.

Each track section is provided with means for supplying an alternating train governing current to the two rails of the section in multiple, which current I will hereinafter term the "loop" current. For this purpose each section between stations is provided with a resistance U connected across the rails adjacent the entrance end of the section, a resistance V connected across the rails at an intermediate point in the section, and a resistance W connected across the ends of the rails at the exit end of the section. Section E—B, which section contains the station with the gauntlet track, is provided with only two of these resistances, U and W, located adjacent the entrance and exit ends of the section respectively. Referring particularly to section B—C, the loop current for this section is supplied by a transformer K^B . When track relay H^C is energized, the loop circuit is from the secondary of transformer K^B , through wire 43, front point of contact 44 of track relay H^C , wire 45, resistance W, the track rails of section B—C in multiple, resistance U, and wire 46 to the secondary of transformer K^B . When track relay H^C is de-energized, the loop circuit is from the secondary of transformer K^B , through wire 43, back point of contact 44 of track relay H^C , wire 47, resistance V, the rails of section B—C in multiple, resistance U, and wire 46 to the secondary of transformer K^B . The primary of transformer K^B is supplied with alternating current from the secondary of transformer F^B , through pole-changing contacts 49 and 52 on relay P^B . When relay P^B is energized, the circuit is from the secondary of transformer F^B , through wire 6, contact 49, wire 50, primary of transformer K^B , wire 51, contact 52, and wire 53 to the secondary of transformer F^B . The current which is then supplied to the loop circuit for section B—C is of what I will term "normal" relative polarity, that is, normal instantaneous polar-

ity with respect to the track circuit current supplied to the section. When relay P^B is de-energized, the circuit is from the secondary of transformed F^B , through wire 6, contact 49, wire 51, primary of transformer K^B , wires 50 and 55, contact 52, and wire 53 to the secondary of transformer F^B . The current which is then supplied to the rails of section B—C is of what I will term "reverse" relative polarity, that is, reverse instantaneous polarity with respect to the track circuit current supplied to the section.

The loop circuits for sections C—D and D—E are the same as the loop circuit for section B—C, the loop current for sections C—D and D—E being furnished by transformers K^C and K^D , respectively. The loop current for section E—B is supplied by a transformer K^E , the primary of which is controlled by relay P^E in the same way that the primary of transformer K^B is controlled by relay P^B . The loop circuit for section E—B is controlled only by front contact 56 of track relay H^B , there being no resistance V at an intermediate point in this section.

The apparatus shown in Fig. 1 is intended for cooperation with train-carried apparatus which operates in the following manner: When a train occupies a portion of track which is supplied with loop current of normal relative polarity and also with track circuit current, the train may proceed at a high speed without incurring an automatic application of the brakes. When the train occupies a portion of track which is supplied with loop current of reverse relative polarity and with track circuit current, the train may proceed at an intermediate speed but if it exceeds this speed it will incur an automatic application of the brakes. When the train occupies a portion of track from which the supply of loop current or track circuit current has been discontinued, the train may proceed at a low speed but if it exceeds this speed it will incur an automatic application of the brakes.

I will first consider only the stretch of track between points B and E in Fig. 1, and will assume that relay P^B is provided only with the circuits traced hereinbefore. If the stretch of track between points B and E is unoccupied, a train moving toward the right will receive a proceed indication throughout section B—C, because relay P^B is energized and will remain energized while the train is in this section, so that loop current of normal relative polarity is supplied to the rails of this section throughout the entire section. If, however, section D—E is occupied and a following train enters section B—C, such following train will at once receive a caution indication, because relay P^B is de-energized due to the fact that track relay H^B is de-energized, and

so loop current of reverse relative polarity is supplied to the rails of section B—C throughout the section. The following train will accordingly incur an automatic brake application at point B if the speed at this point exceeds the intermediate value. If section C—D is occupied and a following train enters B—C, such following train will receive a caution indication at point B and a stop indication upon passing resistance V, because loop current is discontinued at this point due to the fact that track relay H^C is open. The following train will accordingly incur an automatic brake application at point B if the speed is above the low value.

Reverting now to the condition wherein section D—E is occupied and a following train enters sections B—C, it will be remembered that such following train receives a caution indication immediately after passing point B. A caution indication at this point is desirable when the following train is a freight train, because of the relatively long braking distance of trains of this class. If the following train is a passenger train, however, a caution indication, and, consequently, the enforcement of an intermediate speed limit at point B is undesirable, because of the relatively short braking distance for passenger trains. It accordingly becomes desirable to delay the caution indication until the train reaches point C when the train is of the passenger class. To accomplish this result I provide the relay P^B with a pick-up circuit which is controlled by a transformer R^B located in the trackway. This transformer is equipped with a primary winding 57 and a secondary winding 58. The circuit for the primary winding is from the secondary of transformer F^C , through wires 17 and 18, contact 19 of track relay H^C , wires 20 and 20^a, wire 60, primary winding 57, wire 6, common wire 0, and wires 23 and 25 to the secondary of transformer F^C . It will be observed that this circuit is closed if track relay H^C is energized. The circuit for the secondary winding 58 of transformer R^B is from the upper terminal of this winding, through wires 61 and 33, contact 34 of relay H^B , wires 35 and 36, winding of relay P^B , and wires 37 and 6 to the lower terminal of secondary winding 58. This circuit is closed provided that track relay H^B is energized. Transformer R^B is provided with a magnetic circuit having a large air gap and the reluctance of this air gap is so high that unless it is reduced by the means hereinafter explained, the current which is supplied to the pick-up circuit for relay P^B by secondary winding 58 is not sufficient to energize this relay. Each passenger train, however, (see Fig. 2) is provided with a member Q of magnetizable material so disposed that as the train passes transformer R^B this member passes in close proximity to

the transformer and reduces the reluctance of the magnetic circuit to such value that the current supplied to relay P^B by the secondary windings 58 is sufficient to energize this relay. The transformer R^B is so located that relay P^B is picked up before relay H^B opens due to the train entering section B—C. As a passenger train passes point B, then, relay P^B will become energized, and will remain energized as long as such train occupies any part of section B—C because of the stick circuit hereinbefore traced. In other words, with section D—E occupied, a passenger train entering section B—C will cause relay P^B to be energized, so that loop current of normal relative polarity will be supplied to the passenger train throughout section B—C. As will appear hereinafter, if a passenger train enters section C—D while section D—E is still occupied, it will be unable to cause relay P^C to be energized, because the circuit for primary winding 57 of transformer R^C is opened at contact 28 of track relay H^D , and, consequently, the passenger train will receive a caution indication immediately upon entering section C—D. It will, of course, receive a stop indication upon passing resistance V in this section, because track relay H^D is de-energized and so loop current is not supplied to section C—D between resistances V and W.

In describing the structure and operation of the remaining portions of the apparatus shown in Fig. 1, I will first assume that switches N' and N^2 are both in normal positions, that is, that these switches are set up for the passage of passenger trains along the track.

Each relay P is provided with a transformer R similar to transformer R^B , and the pick-up circuit for each relay P including the secondary winding 58 of the associated transformer R is the same as the pick-up circuit for relay P^B . At location D I have provided an auxiliary stick relay X , which is provided with a pick-up circuit including an auxiliary secondary winding 59 on transformer R^D , this pick-up circuit not being controlled by any relay contacts.

The main circuit for relay P^C passes from the secondary of transformer F^B , through wire 13, contact 66 of track relay H^B , contact 67 which is closed only when switch N' is in the reverse position, wire 68, contact 69 of track relay H^E , contact 70 which is closed only when switch N^2 is in the reverse position, contact 71 of track relay H^D , contact 72 of track relay H^C , winding of relay P^C , wire 23, common wire 0, and wire 6 to the secondary of transformer F^B . Switches N' and N^2 being in normal positions, contacts 67 and 70 are open, so that relay P^C is de-energized. It follows that so far as this main circuit is concerned, a train entering section C—D would receive a caution indication regardless

of traffic conditions ahead. The circuit for primary winding 57 of transformer R^C is controlled only by front point of contact 28 of relay H^D , and so if section E—B or B—C is occupied, and the following train is a passenger train, when such train enters section C—D it will cause relay P^C to become energized. Relay P^C will then remain energized as long as the train is in section C—D, because of the stick circuit for relay P^C including contact 74 of relay P^C , back point of contact 31 of track relay H^C and front point of contact 28 of track relay H^D . This train will, therefore, receive a proceed indication through section C—D, and will not receive a caution indication until it reaches point D.

Referring now to the apparatus at point D, the main circuit for relay P^D is from the secondary of transformer F^C , through contact 19 of track relay H^C , front point of contact 65 of track relay H^B , contact 78, wire 77, contact 76 of track relay H^E , contact 88, contact 75 of track relay H^D , winding of relay P^D , and common wire 0 to the secondary of transformer F^C . Contacts 78 and 88 are operated by switches N' and N^2 , respectively, and are closed only when these switches are in the reverse positions; it being assumed that these switches are now in normal positions, these contacts are open and so relay P^D is de-energized. It follows that a train entering section D—E will receive a caution indication at point D in so far as the main circuit for relay P^D is concerned. Winding 57 of transformer R^D is controlled by contact 79 and by contact 80 of track relay H^E . A passenger train entering section D—E will, therefore, energize relay P^D if sections D—E and E—B are both unoccupied, in which event the passenger train will receive a proceed indication in section D—E even if section B—C is occupied. As such train enters section D—E it will cause both relays P^D and X to become energized, whereupon relay X will remain energized as long as the train occupies section D—E because of the stick circuit for this relay including contact 90 of relay X and the back point of contact 28 of relay H^D . Relay P^D will also remain energized by virtue of its stick circuit, which includes contact 81 of relay P^D , back contact 82 of track relay H^D , contact 83 of relay X , contact 79, and contact 80 of track relay H^E . Contact 79 is closed when switch N^2 is in the normal position.

Referring now to the apparatus at point E, the main circuit for relay P^E is from the secondary of transformer F^C , through contact 19 of track relay H^C , contact 65 of track relay H^B , contact 78, wire 77, contact 84 of track relay H^E , winding of relay P^E , and common return 0 to the secondary of transformer F^C . Contact 78 being closed only when switch N' is in the reverse position,

this contact is now open so that relay P^E is de-energized, and so far as the main circuit just traced for this relay is concerned, a train entering section E—B will receive 5 a caution indication. The circuit for the primary winding 57 of transformer R^E is controlled by normal contact 85 on switch N^2 , wire 86, and normal contact 87 on switch N' , and so a passenger train entering section 10 E—B will cause relay P^E to be energized. The stick circuit for relay P^E is controlled only by contact 91 of this relay and back contact 92 of track relay H^E , and so assuming that sections E—B and B—C are unoccupied, the passenger train will receive a 15 proceed indication throughout this section E—B even though section C—D be occupied. Of course, if section E—B is occupied, the passenger train entering this section will 20 receive a stop indication, such indication in fact having been received after having passed resistance V in section D—E.

I will now assume that switches N' and N^2 are reversed, thereby permitting freight 25 trains to proceed along the track. Relay P^C will now become energized, because its main circuit becomes closed at contacts 70 and 67, but this circuit will be opened by a train in section C—D, D—E, E—B or B—C, so 30 that with a train in section E—B or B—C, a following train entering section C—D will receive a caution indication. The main circuit for relay P^D now becomes normally closed at contacts 88 and 78, but with a train 35 in section B—C or C—D, this relay will be de-energized, so that a freight train passing point D will receive a caution indication. Relay X remains de-energized when a 40 freight train passes point D, and so the stick circuit for relay P^D now passes from contact 81 of relay P^D , through back contact 82 of track relay H^D , reverse contact 89 on switch N^2 , and contact 80 of track relay H^E . It follows that if section B—C is occupied, 45 a freight train will receive a proceed indication at this point and through section D—E. Relay P^E is now normally energized because contact 78 in its main circuit is closed, but this relay will be de-energized by a train in section E—B, B—C or C—D, 50 and so with a train in section B—C or C—D, a freight train entering section E—B will receive a caution indication.

To sum up the operation, with section 55 D—E occupied, a freight train will receive a caution indication at B, and a stop indication at V in section C—D, whereas a passenger train will receive a caution indication at C and a stop indication at V in section 60 C—D.

With section E—B occupied, a freight train will receive a caution indication at C and a stop indication at V in section D—E, whereas a passenger train will receive a

caution indication at D and a stop indication at V in section D—E. 65

With section B—C occupied, a freight train will receive a caution indication at C, and a stop indication at E, whereas a passenger train will receive a stop indication 70 at E.

With section C—D occupied, a freight train will receive a caution indication at D, and a stop indication at V in section B—C, whereas a passenger train will receive a 75 caution indication at E and a stop indication at V in section B—C.

Although I have herein shown and described only one form of apparatus embodying my invention, it is understood that various changes and modifications may be made therein within the scope of the appended claims without departing from the spirit and scope of my invention. 80

Having thus described my invention, what 85 I claim is:

1. Railway traffic controlling apparatus comprising a stretch of track used by trains of two classes having different maximum 90 braking distances, and means operating under unsafe traffic conditions to give a restrictive indication on an approaching train at one point or at another point in said stretch according as the train is of one class or the other. 95

2. Railway traffic controlling apparatus comprising a stretch of track divided into sections and used by trains of two different classes having different maximum braking 100 distances, and means operating when a section is occupied to give a restrictive indication on an approaching train at one distance or another in the rear of the occupied section according as the train is of one class or the other. 105

3. Railway traffic controlling apparatus comprising a stretch of track used by passenger trains having relatively short maximum braking distances and by freight trains having relatively long maximum braking distance, and means operating under dangerous traffic conditions to give a restrictive indication on an approaching train at one place a given distance in the rear of the danger point or at another place a greater distance in the rear of the danger point according as the train is of the passenger or the freight class. 110

4. Railway traffic controlling apparatus comprising a stretch of track divided into sections and used by passenger trains having relatively short maximum braking distance and by freight trains having relatively long maximum braking distance, and means operating when a section is occupied to give a restrictive indication on an approaching train at a less or a greater distance in the rear of the occupied section according as 120

the train is of the passenger or the freight class.

5. Railway traffic controlling apparatus comprising a stretch of track used by trains of two classes having different maximum braking distances, means operating under dangerous traffic conditions to give a restrictive indication on an approaching train at least at the greater of said distances in 5 the rear of the danger point, trackway apparatus effective when actuated to prevent said restrictive indication until the train reaches a point at least at the lesser of said distances in the rear of the danger point, and means carried by trains having the lesser maximum braking distance for causing actuation of said trackway apparatus.

6. Railway traffic controlling apparatus comprising a stretch of track used by trains of two classes having different maximum braking distances, means operating under dangerous traffic conditions to give a restrictive indication on an approaching train at least at the greater of said distances in the 10 rear of the danger point, trackway apparatus effective when actuated to prevent said restrictive indication until the train reaches a point at least at the lesser of said distances in the rear of the danger point, a transformer located in the trackway for controlling said apparatus and having a large gap in its magnetic circuit, and a magnetic member carried by each train having the lesser maximum braking distance for reducing the 15 gap in the magnetic circuit of said transformer.

7. Railway traffic controlling apparatus comprising a stretch of track used by trains of two classes having different maximum 20 braking distances, means operating under dangerous traffic conditions to give a restrictive indication on an approaching train at least at the greater of said distances in the rear of the danger point, a relay located in the trackway and effective when energized to prevent said restrictive indication until the train reaches a point at least at the lesser of said distances in the rear of the danger 25 point, and means located partly in the trackway and partly on trains having the lesser braking distance for energizing said relay.

8. Railway traffic controlling apparatus comprising a stretch of track used by trains of two classes having different maximum 30 braking distances, means operating under dangerous traffic conditions to give a restrictive indication on an approaching train at least at the greater of said distances in the rear of the danger point, a relay located in the trackway and effective when energized to prevent said restrictive indication until the train reaches a point at least at the lesser of said distances in the rear of the danger 35 point, a transformer located in the trackway and having a large air gap in its

magnetic circuit, means for supplying the primary of said transformer with alternating current, means for supplying said relay with alternating current from the secondary of said transformer, and a magnetic member carried by each train having the lesser braking distance for reducing the air gap in the magnetic circuit of said transformer.

9. Railway traffic controlling apparatus comprising trackway means normally operating to give a restrictive indication on a train when the train reaches a given location in the rear of a danger point, and apparatus located partly in the trackway and partly on a train for affecting said means to prevent said restrictive indication until the train reaches a location closer to the danger point.

10. In combination, a section of railway track supplied with alternating track circuit current and with alternating loop current, and apparatus located partly in the trackway at the entrance to said section and partly on a train for reversing the instantaneous relative polarity of one of said currents.

11. In combination, a section of railway track supplied with alternating track circuit current and with alternating loop current, a relay for causing one of said currents to be of one instantaneous relative polarity or the other according as said relay is energized or de-energized, and apparatus located partly in the trackway and partly on a train for energizing said relay as the train enters said section.

12. Railway traffic controlling apparatus comprising a stretch of track divided into sections and used by trains of two different classes having different maximum braking distances, means for supplying said section with alternating train governing current, and apparatus located partly in the trackway and partly on each train of one class but not of the other for reversing the instantaneous relative polarity of said current.

13. In combination, a section of railway track supplied with alternating track circuit current, means for supplying said section with alternating loop current of one instantaneous polarity with respect to said track circuit current, and apparatus located partly in the trackway and partly on a train for reversing the relative instantaneous polarity of said loop current as the train enters said section.

14. In combination, a stretch of railway track divided into sections, a transformer for each section having a large gap in its magnetic circuit, means controlled by traffic conditions in advance of each section for supplying alternating current to the primary of the associated section, a relay for each section supplied with current from the secondary of the associated transformer, a magnetic mem-

ber carried by a train for reducing the gap in the magnetic circuit of each said transformer, and traffic governing means controlled by said relays.

5 15. In combination, a stretch of railway track divided into sections, a transformer for each section having a large gap in its magnetic circuit, means controlled by traffic conditions in advance of each section for supplying alternating current to the primary of the associated section, a relay for each section, a pick-up circuit for each relay supplied with current from the secondary of the associated transformer, a holding circuit for 15 each relay controlled by traffic conditions in the associated section and by traffic conditions in advance of the associated section, a magnetic member carried by a train for reducing the gap in the magnetic circuit of 20 each said transformer, and traffic governing means controlled by said relays.

16. In combination, a stretch of railway

track used by trains of two classes having different maximum braking distances, a gauntlet track having two pairs of rails for 25 trains of said two classes respectively, a switch for diverting trains from said stretch to one pair of rails or the other of said gauntlet, means normally operating to give a restrictive indication on a train at a given location in said stretch when the train approaches said gauntlet under unsafe traffic conditions, apparatus located partly in the trackway and partly on trains having the lesser maximum braking distance for affecting 30 said means to delay said restrictive indication until the train reaches a second location closer to the gauntlet, and means associated with said switch for preventing said apparatus from functioning when the switch 35 is set for the passage of trains having the greater maximum braking distance.

In testimony whereof I affix my signature.
HOWARD A. THOMPSON.
